UNITED STATES PATENT OFFICE.

FRANK STEVENS, OF PHILADELPHIA, PENNSYLVANIA.

ELECTRIC SWITCH.

SPECIFICATION forming part of Letters Patent No. 760,815, dated May 24, 1904.

Application filed December 30, 1903. Serial No. 187,129. (No model.)

To all whom it may concern:

Be it known that I, FRANK STEVENS, of the city and county of Philadelphia, State of Pennsylvania, have invented an Improvement in 5 Electric Switches, of which the following is a specification.

My invention has reference to electric switches; and it consists of certain improvements set out in the following specification 10 and shown in the accompanying drawings, which form a part thereof.

My improvement comprehends mechanical constructions making up the details of the switch structure to insure a most positive and 15 effective coöperation of the parts to constitute more especially a two-pole switch, and said mechanism will be better understood by reference to the drawings, in which—

Figure 1 is a sectional plan view of my improved switch, taken on line 1 1 of Fig. 3. Fig. 2 is a vertical side elevation of the same, taken on line 2 2 of Fig. 1. Fig. 3 is a transverse sectional view of the same on line 3 3 of Fig. 2. Fig. 4 is a perspective view of 25 one of the contact-terminals, and Fig. 5 is a sectional view on line 5 5 of Fig. 2.

A is a case of porcelain or other non-conducting material and is made box-shaped and closed on the open side by the face-plate R. 30 This case has metal plates A' secured to its ends, by which it may be secured in position by screws, as shown in Fig. 2.

B is an arch-shaped frame of metal, secured within the box-case, and has pivoted to it at 35 *c* the T-shaped plates C C.

D and D' are two push or thumb pieces and are guided through apertures in the face-plate and hinged, respectively, to the lateral extensions or arms of the plates C C. The 40 lower ends of the downwardly-extending legs of the frames C C are connected together by an insulating-block C' of vulcanite fiber or other insulating material. The transverse block C' is adapted to play through the space 45 below the upper part of the frame B. This block is held in place by insulating-washers C² and flanged studs N N', screwed into the ends of the block and extending over the washers, as shown in Fig. 5.

50 Within the case A are four contact-termi-

nals, and these are widely separated and arranged in pairs—namely, I and H and I' and H'. More specifically, these parts are formed as follows: The terminals H H' are of metal, having at the top clamping-screws M for securing the ends of the circuit-wires and bent at right angles at the bottom to form hinge-supports *e* directly in line with the hinge *c* of the plates C C, as shown in Fig. 2. They are also provided with spring-catches L, extending through apertures in the body of the terminals. The other two terminals I I' are similar in having clamping-screws M for the terminal wires and the spring-catches K, corresponding to the catches L above referred 65 to. These spring-catches are formed of flat metal and extend through apertures in the body of the terminal plates, as shown in Fig. 4. Spring-contact plates J are also secured to the base of these terminals I and rest 70 against each other with their entrance edges flared away from each other, as shown in Fig. 4.

Two contact-blades E F are respectively hinged at *e* and *f* to the base ends of the terminals H H' and are sharpened on one edge to easily enter between the spring-contact plates J. The upper or free ends of these blades are notched to catch upon the spring-catches L and K, as shown in Fig. 2, and 80 whereby they are held against accidental displacement and against movement to such an extent as to require a more positive pull and to insure a quicker movement when released, as more fully described later on.

G G are coil-springs which are connected at one end with the studs N N' and at the other ends with lateral pins on the free ends of the blades E F, as shown in Figs. 2 and 3. The fulcrum or hinge points *c* *e* and *f* being 85 in substantially the same vertical plane it will be seen that as the studs N N' are caused to move to the position shown in Fig. 2, or equally on the other side, the pull by the springs G will cause the free ends of the contact-blades 90 E F to be quickly snapped over from one side to the other, insuring a quick opening and closing of the circuits.

The tops of the contact-blades E F are notched, as at *l*, and in these notches the ends of the 100

spring-catches L K of the terminals snap to retain the blades against accidental or premature displacement under the pull of the springs G. By having the spring-catches extend 5 through apertures in the terminal bodies they are guided and held in proper operative position under the hardest usage of the switch.

In the construction of this switch the terminals have been arranged as far apart as possible 10 and the spaces between the operative parts have been made as large as possible to insure good insulation and protection against short-circuiting.

While I have described my invention as a 15 two-pole switch, it is evident that one set of the terminals and circuit-controlling parts may be used alone to constitute a single-pole switch.

While I prefer the construction shown, the 20 details may be modified without departing from the spirit of my invention.

Having now described my invention, what I claim as new, and desire to secure by Letters Patent, is—

25 1. In an electric switch, the combination of a case of insulating material, four terminal frames secured to the case and separated from each other, spring retaining-catches secured to the terminal frames, spring-contacts secured 30 to two of the terminal frames, contact-blades pivoted to the bases of the remaining two terminal frames, an arch-frame secured to the case and intermediate of the terminal frames and contact-blades, a T-shaped frame pivoted to said 35 arch-frame, push parts adapted to respectively operate upon the opposite arms of the T-shaped frame, and an insulating-spring connection between the free end of each of the contact-blades and the lower end of the T-shaped frame.

40 2. In an electric switch, the combination of a case of insulating material, four terminal frames secured to the case and separated from each other, spring retaining-catches secured 45 to the terminal frames, spring-contacts secured to two of the terminal frames, contact-blades pivoted to the bases of the remaining two terminal frames, an arch-frame secured to the case and intermediate of the terminal frames and 50 contact-blades, a T-shaped frame pivoted to said arch-frame, push parts adapted to respectively operate upon the opposite arms of the T-shaped frame, an insulating-support secured to the end of the T-shaped frame, a spring 55 connection between the free end of each of the contact-blades and the insulating-support of the lower end of the T-shaped frame.

60 3. In an electric switch, the combination of a case of insulating material, four terminal frames secured to the case and separated from each other, spring retaining-catches secured to the terminal frames, spring-contacts secured to two of the terminal frames, contact-

blades pivoted to the bases of the remaining two terminal frames, an arch-frame secured 65 to the case and intermediate of the terminal frames and contact-blades, a T-shaped frame pivoted to the said arch-frame and consisting of two frames arranged one on each side of the arch-frame, two push parts respectively 70 hinged between the arms at each side of the pivot, insulating material secured between the lower parts of the two T-shaped frames and extending through the arch-frame, metal pins secured to each end of the insulating material, and spring connections respectively 75 between said pins and the contact-blades.

4. In an electric switch, a terminal frame consisting of a flat metal body bent at the bottom to form a foot, and at the top to form a 80 binding-post, combined with two spring-contacts secured to the foot and a spring-catch secured to the body and having its free end extended through a hole in the body and terminating above the spring-contacts.

85 5. In an electric switch, a terminal frame consisting of a flat metal body bent at the bottom to form a foot and a hinge member and at the top to form a binding-post, combined with a spring-catch secured to the body and 90 having its free end extended through it.

6. In an electric switch, a terminal frame consisting of a flat metal body bent at the bottom to form a foot and a hinge member and at the top to form a binding-post, combined with a spring-catch secured to the body and having its free end extended through it, a contact-blade pivoted to the hinge member and having its upper end adapted to make connection with the spring-catch, and means 100 to move the contact-blade.

7. In an electric switch, an operating-frame consisting of two T-shaped frames combined with push parts connected to the opposite horizontal arms, an insulating-block interposed between the free ends of the other legs or arms of the T-shaped frame, and pins secured to the insulating-block, in combination with an arch-shaped supporting-frame arranged between the two T-shaped frames and 110 pivoted thereto.

8. In an electric switch, the combination of a pivoted frame consisting of plates C, C, insulating-block C' between them, washers C' of insulating material, pins N, N', screwed 115 into the insulating-blocks and clamping the washers in place, contact-blades, and springs connecting with the contact-blades and also with the pins N, N'.

In testimony of which invention I hereunto 120 set my hand.

FRANK STEVENS.
